UNITED STATES PATENT OFFICE

RALPH E. DODGE, OF SAN FRANCISCO, CALIFORNIA

LIFT BRIDGE

Application filed August 26, 1924. Serial No. 734,270.

The invention relates to lift bridges and particularly to means for counterbalancing the weight of the bridge span.

An object of the invention is to provide a vertically movable bridge span having counterweight levers for counterbalancing the weight of the span, so connected to the span that the lifting effect of the counterweights remains constant for varying angular positions of the counterweight levers.

A further object of the invention is to provide means connecting the counterweight levers with the span so that the force of the counterweights is applied vertically to the span, regardless of the angular position of the levers.

A further object of the invention is to provide a counterbalanced bridge span with means for maintaining accurate counterbalance of the span during its vertical movement.

A further object of the invention is to provide a counterbalanced bridge span with means for moving the span vertically.

The invention possesses other advantageous features, some of which with the foregoing, will be set forth at length in the following description where I shall outline in full that form of the invention which I have selected for illustration in the drawings accompanying and forming part of the present specification. In said drawings I have shown one form of lift bridge embodying my invention, but it is to be understood that I do not limit myself to such form, since the invention, as set forth in the claims, may be embodied in a plurality of forms.

Referring to said drawings:

Figure 1 is a side elevation of a lift bridge constructed in accordance with my invention.

Figure 2 is a plan view of a section of the bridge span, showing the means for raising and lowering the span.

Figure 3 is a cross section taken on the line 3—3 Figure 2.

This invention relates to lift bridges in which the bridge span is vertically movable. In order to facilitate the movement of the span and to reduce the energy required to

move the span, the span is counterbalanced so that only a small amount of power is required to move the span vertically in either direction. The span is usually counterbalanced by counterweight levers fulcrumed on fixed supports at opposite ends of the span, the outer ends of the levers being provided with counterweights and the inner ends of the levers being connected to the span by a simple link.

Due to the fact that the levers assume different angular positions as the span moves vertically, the effective moment produced by the weight varies so that if the lever moment necessary to lift the span does not vary accordingly the effective pull of the counterweight will vary for different positions of the counterweight arm. The inner end of the lever moves in a circle as the lever moves about its fulcrum and consequently such inner end of the lever is displaced laterally with respect to path of moment of the span, as the span is moved vertically. If a single link is employed, connecting the end of the lever with the span, the inclination of this link will vary as the span moves vertically, causing the production of a variable horizontal component of the lifting force.

If the force of the counterweight is divided between a vertical component equal to the weight being lifted and a variable horizontal component then it is clear that the counterweight will not accurately balance the span for all positions. In accordance with my invention, the effective point of application of the counterbalance lever is caused to shift relative to the path of movement of the span so that the magnitude of the horizontal component may be controlled. This horizontal component may be made constant so that the counterweight will always exert the same lifting effect on a span regardless of its position. This is accomplished by connecting the applied end of the counterweight lever to the span at a plurality of spaced points and then providing a linkage connection which will cause the effective points of application to shift between these two points as the applied end

of the counter lever shifts laterally with respect to the movement of the span.

The lift bridge of my invention comprises a span 2 of any suitable construction, which spans the gap between the ends of the two approaches 3. Disposed at each end of the span is a fixed support or tower 4 and fulcrumed on each support is a counterbalancing lever 5, preferably in the form of a truss. The lever preferably extends in the direction of the length of the span and each lever is provided at its outer end with a counterweight 6 of sufficient mass to counterbalance one-half the weight of the span, so that the two counterweights counterbalance the weight of the span.

The span 2 is movable vertically and during such vertical movement, the levers 5 are rocked on their fulcrums 7 so that they assume varying angular positions with respect to the horizontal. The counterweight 6 is attached to the lever at a fixed point of connection, causing the mass of the counterweight to be effective at a fixed point, so that as the lever 5 moves about its fulcrum, the effective lever arm of the counterweight 6 is varied and consequently the counterweight moment is varied. In accordance with my invention I provide means for compensating for this varying counterweight moment, so that the lifting moment applied to the span is substantially equal to the counterweight moment during the angular movement of the lever 5. During the movement of the lever 5 the inner end thereof swings in an arc, so that it has relative horizontal movement with respect to the span. Since the span is to be moved vertically, this relative horizontal movement of the inner end of the lever 5 will tend to break the counterweight force into a horizontal component and a vertical component. Since the horizontal component will vary, the resultant force necessary to produce a vertical component equal to the weight lifted will also vary, thereby causing a variation in the lifting effect of the counterweight, so that the counterweight will not counterbalance the weight of the span. In accordance with my invention, I so connect the end of the lever with the span that the angular movement of the lever in varying the effective counterweight pull, is compensated for so that the counterweight effect remains substantially constant. In the present construction, this is accomplished by means of a rocking lever 12 pivoted intermediate its ends to the inner end of the lever 5. The ends of the rocking lever 12 are connected by cross links 13 and 14 to the span 2 at horizontally spaced points, the spacing of the points and the length of the rocking lever 12, determining the angularity of the links 13 and 14, as the span moves vertically. The length of the rocking lever 12 and

the distance between the points of connection of the links 13 and 14 to the span is such that the effective point of application of the span shifts as the angularity of the counterweight lever is varied.

The vertical distance between the fulcrum of the rocking lever 12 and a horizontal line in the span, remains substantially constant as the counterweight lever moves about its fulcrum, indicating that any horizontal force components that may exist remain substantially constant so that the counterweight is effective to produce a substantially constant vertical force. I prefer to construct the span and the counterweight levers so that the system will operate as if the centers of mass of the system lie below the fulcrums 7. When the counterweight levers are horizontal, the centers of mass of the span, levers and counterweights will lie vertically below the fulcrums 7 and as the angularity of the levers 5 varies, the centers of mass are simultaneously moved outward or inward below the fulcrums 7. That is, the system is adapted to be slightly off balance so that the system is therefore in the nature of a pendulum, with its position of rest occurring when the levers 5 are horizontal. There is therefore a force tending to raise the span from its lower position and this force gradually diminishes as the span approaches its halfway position and from there upward the force occasioned by the off balancing of the system is in the downward direction. In raising the span this force assists in overcoming the inertia of the span during half of its movement and opposes the momentum of the span during the last half of its movement. The same effect is produced when the span is lowered, so that the amount of energy required to move the span is reduced to a minimum. This effect also serves to reduce the wear on the brakes which are used for stopping the movement of the span.

Means are provided for moving the span vertically and due to the counterbalancing of the weight of the span, only a small amount of energy is required to move the span. Secured to each support 4 midway between the sides of the span is a rack 15, which is vertically arranged and which is engaged by a pinion 16 secured to the shaft 17 journalled on the span. The shaft 17 carries a gear 18 which meshes with a pinion 19 on the drive shaft 21 which extends longitudinally of the span from end to end and which is connected to a driving motor 22 through a suitable speed reducing gearing 23. The pinion 16 is held from lateral movement with respect to the rack 15 by the flanged guide rollers 24 mounted on the shaft 17, with the flanges engaging the sides of the rack. The pinion 16 is held in mesh with the rack 15 by a roller 25.

mounted on a shaft secured to the span and bearing against the rack support 26 on the opposite side of the rack. By making the gears 18 and 19 of different widths, one gear may slide longitudinally with respect to the other, due to thermal expansion of the span, without becoming disengaged. For this same reason the shaft 17 floats longitudinally in its bearings on the span, to permit the bearings to move longitudinally, without causing longitudinal movement of the shaft 17, as the span expands and contracts.

By virtue of this construction, the span is moved vertically into and out of position between the ends of the approaches 3, is substantially counterbalanced in all of its positions, and is movable vertically by the expenditure of a small amount of energy.

While I have described the present invention as embodied in a lift bridge it is to be understood that the invention is not limited to a lift bridge, but may be employed in connection with any vertically movable structure, such as an elevator platform or floor and by the word "span" it is to be understood that I mean a bridge span or its equivalent, in the present instance, comprising any vertically movable structure.

I claim:

1. In a device of the class described, a span adapted to be moved thru a given path, a support adjacent said span, a pivoted counterbalance lever mounted on said support, one end of said lever extending over said span, a plurality of links connecting said end of the lever with two spaced points on the span whereby the effective point of application of the force of the lever is caused to shift between said points for different positions of the span.

2. A bridge comprising a vertically movable span, a fixed support at each end of the span, levers fulcrumed on said supports, a rocking lever fulcrumed on each lever and links connecting each rocking lever to spaced points on the span.

3. A bridge comprising a vertically movable span, a fixed support at each end of the span, levers fulcrumed on said supports, a rocking lever fulcrumed on each lever and cross links connecting the ends of each rocking lever with the span at spaced points.

4. A bridge comprising a vertically movable span, a fixed support at each end of the span, levers fulcrumed on fixed pivots on said supports, counterweights on the outer ends of said levers, a rocking lever pivoted to the inner end of each lever and cross links connecting the ends of each rocking lever with the span at fixed points.

In testimony whereof, I have hereunto set my hand.

RALPH E. DODGE.
